UNITED STATES PATENT OFFICE.

WILLIAM A. JAMES, OF ST. LOUIS, MISSOURI.

SULKY-PLOW.

SPECIFICATION forming part of Letters Patent No. 224,188, dated February 3, 1880.

Application filed December 4, 1879.

To all whom it may concern:

Be it known that I, WILLIAM AUSTIN JAMES, of St. Louis, in the county of St. Louis and State of Missouri, have invented a new and useful Improvement in Sulky-Plows, of which the following is a specification.

Figure 1, Sheet 1, is a sectional side elevation of my improvement, taken through the line *x x*, Fig. 2. Fig. 2, Sheet 1, is a sectional plan view. Fig. 3, Sheet 2, is a sectional side elevation taken through the line *y y*, Fig. 2. Fig. 4, Sheet 2, is a rear elevation. Figs. 5, 6, 7, 8 represent a modification.

The object of the present invention is to produce a ready and convenient adjustment of the plow, as hereinafter particularly described in connection with the drawings.

Similar letters of reference indicate corresponding parts.

20 A are the wheels, and B is the axle, of the sulky. The axle B has a crank, C, formed upon its middle part, and is twisted so that when the left arm of the crank C is horizontal its right arm may incline upward at an angle 25 of forty degrees, or nearly so, as shown in Fig. 1. The left arm of the crank, that carries the land-wheel, should be a little longer than the right arm, that carries the furrow-wheel, so that the two wheels A will always be opposite 30 each other, or nearly so.

D is the beam, E is the land-side, and F is the mold-board, of an ordinary plow. The plow-beam D rests upon the center of the bar G, the ends of which are bent downward and 35 have holes formed through them to receive the middle part of the axle-crank C. The plow-beam D rests between two low stops, H, attached to the bar G, and is secured in place by two angle-irons, I, the upper arms of which 40 are secured to the opposite sides of the beam D by a bolt, J, passing through them and through the said beam. The lower arms of the angle-irons I are secured to the bar G by bolts K. With this construction, by loosening 45 the three bolts J K K the plow may be turned toward its land-side or toward its mold-board, as may be required, and by tightening the said bolts the plow will be held securely in place. The plow is further strengthened in 50 position by the two inclined braces L, the for-

ward ends of which are bolted to the end parts of the bar G.

The rear ends of the braces L have screw-threads formed upon them, are passed through lugs M, attached to the opposite sides of the beam D, and have nuts N screwed upon them upon the opposite sides of the lugs M. With this construction the plow may be adjusted with its point toward the land by loosening the three bolts J K K, the forward nut N upon 55 the left brace L, and the rear nut N upon the right brace L.

When the plow is to be adjusted with its point from the land the three bolts J K K are loosened, and the forward nut N upon the 60 right brace, and the rear nut N upon the left brace. When the plow has been adjusted it is held securely in place by tightening the bolts J K K and the nuts N.

The bar G turns freely upon the crank-axle 70 B, and may be made detachable by slotting its ends to receive the said axle B. In this case the bar G is secured in place upon the axle B by the blocks O, which have projections formed upon one side to fit into the slots of 75 the bar G and notches in their upper ends to receive the axle B, and are bolted to the slotted ends of the bar G, as indicated in Figs. 5, 6, 7, 8.

P is a bent or arched bar, the left arm of which has a hole formed through its end to 80 receive the axle B. The right arm of the arched bar P has a hole formed through its end to receive the bolt Q, by which it is hinged to the outer end of the arm R. The inner end of the arm R has a hole formed through it to 85 receive the axle B, to which it is secured by a set-screw, S. With this construction the arched bar P will be held vertical however the axle B may be adjusted.

T is the driver's seat, which is connected 90 with the top of the arched bar P by a spring-standard, U, or other suitable means.

V is the tongue, or a bar to which the tongue is attached. The tongue or bar V is bolted to the upper part of the right arm of the arched 95 bar P, and is strengthened in position by the braces W, the forward ends of which are bolted to the opposite sides of the tongue or bar V. The rear ends of the braces W are bolted to the arms of the arched bar P near 100

their ends. The braces W are strengthened by a cross-bar, X, bolted to their forward parts.

Y is a lever, the lower end of which is inserted in a socket, Z, where it is secured in place by a screw or bolt, a. The lower part of the socket Z has a transverse hole formed through it to receive the axle B, to which it is secured by a set-screw, b, so that the axle B may be turned to adjust the plow and level the machine by operating the lever Y. The lever Y moves along a notched bar, c, and is provided with a flange or catch, d, to engage with the notches of the said bar c and hold the said lever Y securely in any position into which it may be adjusted. The notched bar c is arched, and its ends are curved inward and upward and are secured to the bar or tongue V. The lever Y is held against the notched bar c by a spring, e, which rests against the inner side of the said lever Y, and

its lower end is secured to the socket Z. With this construction, by operating the lever Y the plow may be adjusted to run at any desired depth in the ground, and raised away from the ground, the sulky being all the time held level.

Having thus fully described my invention, I claim as new and desire to secure by Letters Patent—

In a sulky-plow, the combination, with the crank C of the axle B and the beam D of a plow, of the bent bar G, provided with stops H, the angle-irons I, adjusting-bolts, and the adjusting-braces L, substantially as herein shown and described, so that the plow may have the adjustments as set forth.

WILLIAM AUSTIN JAMES.
